Primary Examiner — Eric L Goodman*Assistant Examiner* — Steven J Czyz(74) *Attorney, Agent, or Firm* — Kilpatrick Townsend & Stockton LLP(57) **CLAIM**

The ornamental design for a baby carrier with ties, substantially as shown and described.

DESCRIPTION

FIG. 1 is a perspective view of a baby carrier with ties showing my new, original, and ornamental design when worn by a user;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a front view of the baby carrier with ties, shown when not worn by a user and in an open configuration; and, FIG. 8 is a rear view of the baby carrier with ties, shown when not worn by a user and in an open configuration.

The broken lines depict environment and portions of the article that form no part of the claimed design.
